(57) **CLAIM**

The ornamental design for a hair collecting device, as shown and described.

DESCRIPTION

FIG. 1 shows a perspective view of a hair collecting device in an open configuration;

FIG. 2 shows a front view of the hair collecting device in an open configuration;

FIG. 3 shows a rear view of the hair collecting device in an open configuration;

FIG. 4 shows a right-side view of the hair collecting device in an open configuration;

FIG. 5 shows a left-side view of the hair collecting device in an open configuration;

FIG. 6 shows a top plan view of the hair collecting device in an open configuration;

FIG. 7 shows a bottom plan view of the hair collecting device in an open configuration; and,

FIG. 8 shows a side perspective view of separate components of the hair collecting device in an exploded view. The shade lines in the Figures show contour and not surface ornamentation.

1 Claim, 8 Drawing Sheets
